Assistant Examiner — Grace Doyle

(57) **CLAIM**

The ornamental design for a snap hook as shown and described.

DESCRIPTION

1. Snap hook
2. Snap hook
- 1.1 : Perspective
- 1.2 : Front
- 1.3 : Back
- 1.4 : Right
- 1.5 : Left
- 1.6 : Top
- 1.7 : Bottom
- 1.8 : Perspective, in open configuration
- 1.9 : Right, in open configuration
- 1.10 : Perspective
- 1.11 : Perspective
- 2.1 : Perspective
- 2.2 : Front
- 2.3 : Back
- 2.4 : Right
- 2.5 : Left
- 2.6 : Top
- 2.7 : Bottom
- 2.8 : Perspective, in open configuration
- 2.9 : Right, in open configuration
- 2.10 : Perspective
- 2.11 : Perspective

The evenly spaced dashed lines in reproductions 1.1, 1.3-1.5, 1.8-1.11, 2.1, and 2.3-2.11 depict portions of the snap hook that form no part of the claim. The broken line showing of jewelry in reproductions 1.10, 1.11, 2.10, and 2.11 is for the purpose of illustrating environmental subject matter and forms no part of the claimed design. The dot-dash broken

(Continued)

lines in reproductions 1.11 and 2.11 depict the break lines of the environmental subject matter that form no part of the claimed design.

1 Claim, 22 Drawing Sheets
